ARRANGEMENT OF OPPOSED
SUPERCHARGERS

Chester R. Wells, Rocky Hill, Conn., assignor to
United Aircraft Corporation, East Hartford,
Conn., a corporation of Delaware

Application June 17, 1948, Serial No. 33,456

15 Claims. (Cl. 230—11)

1 This invention relates to superchargers and particularly to an arrangement of a pair of superchargers arranged to operate in parallel.

Where conditions are such that the required quantity of air for supercharging cannot be delivered by a single impeller wheel, the size of which is limited by the engine installation, it may be advantageous to operate supercharger wheels in parallel. A feature of this invention is an arrangement of supercharger wheels on opposite sides of a crankcase section with a common drive from the engine for both wheels.

When superchargers are so arranged, the thermal expansion of the crankcase section may change the spacing between the supercharger casings and thus produce an undesirable change in the clearance between the interconnected supercharger impellers and the adjacent walls of the casings especially where the opposite impellers are directly connected together. A feature of this invention is an arrangement by which to compensate for the change in the spacing of supercharger casings by producing a corresponding change in the spacing of the impellers. More specifically, a feature of the invention is the interconnection of the impellers in such a manner that the impellers will be caused to move apart axially the same amount that the casings are moved during thermal expansion of the supporting crankcase section.

Other objects and advantages will be apparent from the specification and claims, and from the accompanying drawings which illustrate an embodiment of the invention.

Fig. 1 is a vertical sectional view through an airplane nacelle showing the installation of the two stage engine.

Fig. 2 is a perspective view showing the arrangement of the auxiliary supercharger stage.

Fig. 3 is a longitudinal vertical sectional view through the rear section of the engine.

Fig. 4 is a horizontal sectional view along the line 4—4 of Fig. 3.

Fig. 5 is a view of a part of Fig. 4 on a somewhat larger scale showing the construction of the impeller shaft and showing the coupling assembly in section.

Referring first to Fig. 1, showing an engine with two stages of supercharge, the airplane nacelle 20 encloses an aircraft engine 22 supported as by a frame 24, the engine being connected to the frame as by mounting brackets 26. The engine shown is of the multiple-row radial type in which the crankcase 28 supports the cylinders 30 and has a nose section 32 incorporating the reduction

2 gear, not shown, for the propeller system 34. The nose section also carries one or more accessories 36.

Crankcase 28 has a rear section 38 within which is enclosed the main supercharger and its drive together with a drive for other accessories 40 hereinafter described in greater detail. The rear section supports on opposite sides the casings 42 and 44 for the impellers of the auxiliary supercharger stage.

Air enters the supercharger casings through ducts 46 and 48, Fig. 1, communicating with the centrally located openings 43 and 45, Fig. 4, in the casings 42 and 44. Air compressed by the auxiliary compressor stages may be discharged from the casings 42 and 44 into one or more intercoolers 50 and thence to the duct 52 leading to the carburetor 54 and from there to the main supercharger 56, Fig. 3. A flap valve 58 may be provided in the duct 52 to admit air directly from an inlet 60 to the main supercharger stage when the auxiliary stage is not in operation.

Referring now to Fig. 3, the impeller 62 for the main supercharger stage is driven from the accessory drive shaft 64 which is connected to the crankshaft 66 by a change speed gearing. This gearing includes a fixed ring gear 68 meshing with one or more pinions or planet gears 70 on a shaft 72 in a cage 74 attached to the end of the crankshaft. The planet gear, of which there would normally be a group spaced circumferentially around the crankshaft, meshes with a sun gear 76 on the accessory shaft to drive the accessory shaft substantially faster than the crankshaft and preferably at a speed three times that of the crankshaft. This specific arrangement of drive is described and claimed in the copending Hasbrouck application Serial No. 33,515, filed June 17, 1948 now Patent No. 2,595,942.

The accessory shaft 64 carries a driving gear 78, the hub of which is splined to the shaft and provides a bearing surface for the shaft within a bracket 80 which is fastened within the crankcase section 38. The gear 78 meshes with a gear 82 on a shaft 84 journalled in the bracket 80 and in a bearing 86 provided by the rear crankcase section. Shaft 84 carries another gear 88 meshing with a gear 90 splined to the sleeve 92 on which the impeller 62 is mounted. The supercharger casing 94, within which the impeller 62 is located, interconnects the main crankcase section 26 and the rear section 38.

The accessory shaft also drives other accessories, such as the starter or generator 40 through a series of interconnecting gears 100 connecting

with a gear 102 also splined to the accessory shaft 64. The particular accessory drive arrangement is described in the copending application of Hasbrouck Serial No. 33,515, filed June 17, 1948 now Patent No. 2,595,942.

As shown in Fig. 4, the drive for the auxiliary stage impellers 104 and 106 is from the same gear 78 that drives the main impeller. The impellers 104 and 106 are mounted on opposite ends of a shaft assembly 110 driven in the low speed range through a gear 112 meshing with gear 78 and a low ratio hydraulic coupling 114 delivering power to a bevel gear 116 meshing with a pinion 118 having a drive connection with the shaft assembly 110. The auxiliary stage impellers are driven in the high speed range through a gear 120 in mesh with the gear 78 and meshing in turn with a gear 122. The latter drives a bevel gear 124 through a hydraulic coupling 126, the bevel gear 124 meshing with a pinion 128 connected to the impeller shaft assembly 110.

The shaft assembly includes a central impeller connecting rod 130 having tie bolts 132 and 134 threaded into opposite ends of the rod and forming extensions of it. Each bolt has a flange 136, Fig. 5, engaging the end of the rod and each bolt is fastened in the rod by a pin 138. The impellers 104 and 106 are mounted on sleeves 140 and 142, preferably with a shrink fit, and are clamped thereon as by a nut 144. The sleeves 140 and 142 are mounted on the ends of the connecting rod and associated tie bolts, and are clamped thereon by nuts 146. Each of the sleeves has an internal shoulder 148 engaging with a spacer ring 150 to maintain the desired spacing between the impellers.

The inner ends of sleeves 140 and 142 are both splined to a connecting quill 152 in such a manner that the sleeves will rotate in unison although they are free to move axially with respect to each other. The sleeves 140 and 142, and the connecting rod 130 and tie bolts 132 and 134, form, with quill 152, the shaft assembly 110 that interconnects the impellers.

Each sleeve 140 and 142 has a driving hub 153, Fig. 5, mounted thereon and having a spline connection 154 with the associated sleeve. Each hub has an annular flange 156 receiving a centrally located boss 158 on the adjacent impeller for driving it. Thus both impellers rotate as a unit on the interconnecting shaft assembly which permits thermal expansion between the opposed impellers.

For driving the shaft assembly 110, the sleeves 140 and 142 carry surrounding sleeves 162 and 164 splined to the sleeves 140 and 142, respectively, and axially slidably thereon, the outer surrounding sleeves forming bearing surfaces for the shaft assembly. The shaft assembly is journaled centrally in bearings 166 in the bracket 80 mounted, as above stated, in the rear crankcase section 38. Adjacent each impeller, as best shown in Fig. 5, the assembled shaft is journaled in bearing sleeves 167 and 169 in backing plates 168 and 170 (Fig. 4), respectively, which form the back walls of the impeller casings 42 and 44. These plates 168 and 170, as shown in Figs. 4 and 5, are mounted on opposite sides of the crankcase section 38. In addition to providing bearings for the assembled shaft, the plates form the back closure plates for the casings 42 and 44. The front plates or scrolls 172 and 173 for the casings are attached at their edges to the plates 168 and 170 respectively, and support the diffuser rings 174 and 175.

The plates 168 and 170 are arranged to support the driving mechanisms for the auxiliary supercharger stage. As best shown in Figs. 4 and 5, the plate 168 provides bearings 176 for the shaft 178 for the low ratio drive. The plate 170 provides similar bearings 180 for the shaft 182 of the high ratio drive. The drive connections for the low and high ratio drives for the supercharger stage are similar, except for the gear ratio, and a description of the low ratio drive will suffice. As shown in Fig. 5, the gear 112 is splined to a sleeve 186 on which the impeller 188 of the low ratio coupling 114 is mounted. The runner 190 of the coupling is splined to the shaft 178 to which the bevel gear 116 is also splined. The supply of fluid to the coupling may be through a passage 192 in plate 168 and through a ported plug 194 in the shaft 178.

Also, as shown in Fig. 5, the gear 118, which is driven from the gear 116, has a spline connection with the sleeve 162 and is held in fixed axial position thereon by locking rings 196. The gear 118 is backed up by a thrust bearing ring 198 which engages with a cooperating ring 200 supported by the bearing ring 167 in plate 168 for limiting the axial movement of the gear 118. Gear 128 is fastened to sleeve 164 in a similar manner and is backed up by a thrust bearing 202, Fig. 4. The assembled shaft is free to slide axially within the sleeves 162 and 164, thereby permitting the axial thrust on the opposed impellers to balance out. It may be noted that the gears 118 and 128 are retained in predetermined relation to the axes of gears 116 and 124 by the thrust bearings and independently of the thermal expansion of the crankcase section 38 since the gears 116 and 118 are both supported by the plate 168 and both gears 128 and 130 are supported by the plate 170.

The material of the impeller connecting rod 130 is so selected that its total longitudinal thermal expansion will correspond almost exactly to the total transverse thermal expansion of the crankcase section 38. Thus, if the plates 168 and 170 are caused to move apart by the thermal expansion of the crankcase section, the corresponding thermal expansion of the rod 130 will produce an increase in the spacing between the impellers 104 and 106, thereby to assure a maintenance of the proper clearance between the impellers and the adjacent surfaces of the surrounding casing regardless of the operating temperature of the parts of the power plant.

Since the normal operating temperature of the rod 130 may be different from the normal operating temperature of crankcase section 38, the length and material of rod 130 for the purpose of equalizing the thermal expansions, may be determined by tests by which the operating temperatures and, therefore, the required changes in dimension may be ascertained. In the arrangement shown, a magnesium rod was used in conjunction with a magnesium rear crankcase section, and the rod was made nearly the same length as the transverse dimension of the rear case. Obviously, other dimensions and material might be used where necessary to balance the thermal expansions.

In assembly of the auxiliary superchargers, the sleeves 162 and 164 are mounted within the supporting plates 168 and 170 and in the bearings 166 in bracket 80. Quill 152 is placed in position before assembly of the sleeves 162 and 164. One of the impellers with its attached sleeve 75 is then mounted and the central shaft with its

attached bolts is inserted. The other impeller and sleeve are then added and the clearance for the impellers are checked. The proper clearance is obtained by inserting a spacer ring or spacer 150 of the necessary length. The clamping nuts 146 are then tightly secured and the impeller assembly is complete. The diffuser elements and the scrolls are then placed in position over the impellers and secured to the remainder of the unit. It will be apparent that the sleeves 162 and 164 may have been mounted in proper relation to the plates 168 and 170 during the assembly of the impeller driving means on said plates. The sleeves 162 and 164 will then be a part of the sub-assembly of the driving mechanism and fluid coupling that is mounted on the plate 168 or 170.

I claim:

1. In a power plant, an engine and a supercharger arrangement, the latter including an impeller mounted on each side of said engine, a shaft assembly connecting said impellers and being supported by said engine, two separate driving means mounted between said engine and said shaft assembly for selectively driving the impellers, each driving means including a surrounding sleeve mounted around said shaft assembly and being splined thereto.

2. In a power plant, an engine and a supercharger arrangement, the latter including an impeller mounted on each side of said engine, a shaft assembly connecting said impellers and being supported by said engine, two separate driving means mounted between said engine and said shaft assembly for selectively driving the impellers, each driving means including a hydraulic coupling and a surrounding sleeve mounted around and splined to said shaft assembly.

3. In a power plant, an engine having a crank-shaft, a pair of supercharger impellers, one mounted on each side of said engine, a shaft assembly connecting said impellers, two separate driving means mounted between said crankshaft and said shaft assembly, each driving means including a sleeve around and splined to said shaft assembly.

4. In a power plant, an engine having a crank-shaft, a pair of supercharger impellers, one mounted on each side of said engine, a shaft assembly connecting said impellers, two separate driving means mounted between said crankshaft and said shaft assembly, each driving means including a hydraulic coupling and a surrounding sleeve mounted around and splined to said shaft assembly.

5. In a power plant, an engine having a crank-shaft, a pair of supercharger impellers, one mounted on each side of said engine, a shaft assembly connecting said impellers, two separate driving means mounted between said crankshaft and said shaft assembly, each driving means including a hydraulic coupling, gearing for transmitting the drive from the crankshaft to the coupling and a bevel gearing for transmitting the drive from each coupling to the impeller shaft assembly, each bevel gearing including a bevel gear connected to a surrounding sleeve mounted around said shaft assembly, each surrounding sleeve being splined to said shaft assembly.

6. In a supercharging device, a supporting member, a supercharger mounted on each side of said member, each supercharger including an impeller, and a shaft assembly journalled in said

member and extending between and supporting said impellers, said shaft assembly including a connecting rod, a sleeve mounted on each end of said rod for supporting said impellers, and a quill surrounding the inner ends of said impeller supporting sleeves and being splined thereto.

7. In a supercharging device, a supporting member, a supercharger mounted on each side of said member, each supercharger including an impeller, and a shaft assembly journalled in said member and extending between and supporting said impellers, said shaft assembly including a connecting rod, a sleeve mounted on each end of said connecting rod, said sleeves supporting the impellers, and tie bolt means mounted on the ends of the connecting rod for securing the sleeves to their respective ends of the connecting rod.

8. In a supercharging device, a supporting member, a supercharger mounted on each side of said member, each supercharger including an impeller, and a shaft assembly journalled in said member and extending between and supporting said impellers, said shaft assembly including a connecting rod, a sleeve mounted on each end of said connecting rod, means supporting each sleeve against axial movement on the rod at the end thereof, said sleeves supporting the impellers, said connecting rod being of a material to have a thermal expansion equal to the thermal expansion of the supporting member.

9. In a supercharger arrangement, a supporting member, superchargers fixedly mounted on opposite sides of said member each including an impeller and a casing, and a shaft assembly supported by said member and supporting said impellers including a connecting rod, a sleeve mounted on each end of said connecting rod, means supporting each sleeve against axial movement on the rod at the outer ends thereof, a quill surrounding the inner ends of said sleeves and being splined thereto to permit the sleeves to rotate in unison while leaving them free to move axially with respect to each other, said sleeves supporting the impellers at their outer ends.

10. In a power plant, an engine and a supercharger arrangement, the latter including an impeller mounted on each side of said engine, a shaft assembly connecting said impellers and being supported by said engine, and two separate driving means mounted between said engine and said shaft assembly for selectively driving the impellers, said shaft assembly including a connecting rod and a sleeve mounted and fixed on each end of said rod, each driving means having a surrounding sleeve mounted around one of said sleeves of said shaft assembly, each surrounding sleeve being splined to its cooperating shaft assembly sleeve.

11. In a power plant, an engine and a supercharger arrangement, the latter including an impeller mounted on each side of said engine, a shaft assembly connecting said impellers and being supported by said engine, and two separate driving means mounted between said engine and said shaft assembly for selectively driving the impellers, said shaft assembly including a connecting rod, a sleeve mounted on said connecting rod at each end of said rod, means supporting each sleeve against axial movement on the rod at the outer ends thereof and a quill surrounding the inner ends of said sleeves and being splined thereto to permit the sleeves to rotate in unison while leaving them free to move axially with respect to each other, said sleeves supporting

the impellers at their outer ends, each driving means having a surrounding sleeve mounted around and attached to one of said shaft assembly sleeves and being located between said quill and said impeller.

12. In combination, an engine, a supercharger mounted on each side of said engine, each supercharger including a casing and an impeller, a shaft assembly mounted in said engine and supporting said impellers, said shaft assembly including a connecting rod, a first sleeve having one end bolted to one end of said rod, a second sleeve having one end bolted to the other end of said rod, the free ends of said sleeves being positioned intermediate the ends of said rod, and a quill surrounding the free ends of said sleeves and being splined thereto, one impeller being mounted on the bolted end of each of said sleeves.

13. In combination, an engine, a supercharger mounted on each side of said engine, each supercharger including a casing and an impeller, a shaft assembly mounted in said engine and supporting said impellers, said shaft assembly including a connecting rod, said rod having an internally threaded recess at each end, a first sleeve having two internal bores of different diameters, the larger of the two bores having sliding engagement with one end of said rod, a first tie bolt, said first bolt being threadably engaged at one end in the internally threaded recess of said one end of said rod and extending through the smaller of the two bores of said sleeve, a first nut threadably engaging the other end of said first tie bolt to hold said first sleeve on said connecting rod, a second sleeve having two internal bores of different diameters, the larger of the two bores having sliding engagement with the other end of said rod, a second tie bolt, said second bolt being threadably engaged at one end in the internally threaded recess of said other end of said rod and extending through the smaller of the two bores of said second sleeve, a second nut threadably engaging the other end of said second tie bolt to hold said second sleeve on said connecting rod, the free ends of said sleeves being positioned intermediate the ends of said rod, and a quill surrounding the free ends of said sleeves and being splined thereto, one impeller being mounted on the bolted end of each of said sleeves.

14. In combination, an engine, a supercharger mounted on each side of said engine, each supercharger including a casing and an impeller, a shaft assembly mounted in said engine and supporting said impellers, said shaft assembly including a connecting rod, said rod having an internally threaded recess at each end, a first sleeve having two internal bores of different diameters, the larger of the two bores having sliding engagement with one end of said rod, a first tie bolt, said first tie bolt being threaded on each end and having a flange at the end of the threaded portion of one end, said first tie bolt being threaded into one threaded recess of said rod with the flange of said bolt resting against the end of said rod, said tie bolt extending through the smaller of the two bores of said sleeve, a first nut threadably engaging the other end of said first tie bolt to hold said first sleeve on said connecting rod, a second sleeve having two internal bores of different diameters, the larger of the two bores having a sliding engagement

with the other end of said rod, a second tie bolt, said second tie bolt being threaded on each end and having a flange at the end of the threaded portion of one end, said second tie bolt being threaded into the other threaded recess of said rod with the flange of said bolt resting against the end of said rod, said tie bolt extending through the smaller of the two bores of said second sleeve, a second nut threadably engaging the other end of said second tie bolt to hold said second sleeve on said connecting rod, the free ends of said sleeves being positioned intermediate the ends of said rod, and a quill surrounding the free ends of said sleeves and being splined thereto, one impeller being mounted on the bolted end of each of said sleeves.

15. In combination, an engine, a supercharger mounted on each side of said engine, each supercharger including a casing and an impeller, a shaft assembly mounted in said engine and supporting said impellers, said shaft assembly including a connecting rod, said rod having an internally threaded recess at each end, a first sleeve having two internal bores of different diameters, the larger of the two bores having sliding engagement with one end of said rod, a first tie bolt, said first tie bolt being threaded on each end and having a flange at the end of the threaded portion of one end, said first tie bolt being threaded into one threaded recess of said rod with the flange of said bolt resting against the end of said rod, said tie bolt extending through the smaller of the two bores of said sleeve, a first spacer located between the flange and the shoulder formed by the intersections of the bores of different diameters in the first sleeve, a first nut threadably engaging the other end of said first tie bolt to hold said first sleeve on said connecting rod, a second sleeve having two internal bores of different diameters, the larger of the two bores having a sliding engagement with the other end of said rod, a second tie bolt, said second tie bolt being threaded on each end and having a flange at the end of the threaded portion of one end, said second tie bolt being threaded into the other threaded recess of said rod with the flange of said bolt resting against the end of said rod, said tie bolt extending through the smaller of the two bores of said sleeve, a second spacer located between the flange and the shoulder formed by the intersections of the bores of different diameters in the second sleeve, a second nut threadably engaging the other end of said second tie bolt to hold said second sleeve on said connecting rod, the free ends of said sleeves being positioned intermediate the ends of said rod, and a quill surrounding the free ends of said sleeves and being splined thereto, one impeller being mounted on the bolted end of each of said sleeves.
